UNITED STATES PATENT OFFICE.

WILLIAM H. RICKEY, OF EAST ORANGE, NEW JERSEY.

EDGE-IRONING MACHINE.

SPECIFICATION forming part of Letters Patent No. 660,277, dated October 23, 1900.

Application filed December 1, 1899. Serial No. 738,761. (No model.)

To all whom it may concern:

Be it known that I, WILLIAM H. RICKEY, a citizen of the United States, and a resident of East Orange, in the county of Essex and State 5 of New Jersey, have invented certain new and useful Improvements in Edge-Ironing Machines, of which the following is a specification.

My invention relates to ironing-machines, 10 and more particularly to the class known as "edge-ironers." It is especially applicable to ironing the edges of collars and cuffs, but may also be used for putting a smooth and perfect edge on other varieties of starched goods.

15 One object of my invention is to furnish an edge ironer which shall be easy to manipulate, rapid in its operation, and economical in construction.

A further and special object is to furnish a 20 machine which, having the qualities before enumerated, shall enable collars and similar articles having a curved or irregular edge to be dampened, polished, and smoothed down at one simple and rapid operation.

25 To attain these advantages, I unite in one machine a dampener pivotally mounted and one or more pivotally-mounted smoothing and polishing irons in line therewith, the said dampener and iron or irons being so arranged 30 that they will automatically furnish the requisite pressure and follow exactly the shape of the article operated upon.

In the drawings, Figure 1 is a view of the machine at work looked at from above and 35 showing the various positions assumed by the separate irons when a curved edge is being ironed. Fig. 2 is a front view; Fig. 3, a vertical section through the center of the dampener; Fig. 4, a vertical section through one 40 of the irons. Fig. 5 is a section of the upper projecting guide, showing the arrangement for avoiding the edge of the articles being caught when pushed through the ironer. Fig. 5^a shows more plainly the rounded edge of 45 the guide, and Fig. 5^b a cross-section of the guide on the line xx of Fig. 5^a. Fig. 6 shows a method of mounting the irons or dampener so that they may recede in grooves, and Fig. 7 is a vertical section through the lines 6 6 of 50 Fig. 6 looking in the direction of the arrow.

Referring to the drawings, $a a a$ are the irons swinging on the pivots $b b b$.

c is the dampener, pivotally mounted at b' . $d d$ are weights, either fixed at the end of the levers e or adjustable along them. These levers swing on the fulcrums f , and by means of the arm g , resting against the irons and dampener, they control by their weight the motions of the irons a and of the dampener c . 55

h is a hook at the end of the arm g , which 60 rests against and slides along the outer edge of the iron and dampener, the iron and dampener being provided with a projection h' , which limits the movement of the iron and dampener and prevents the hook h from sliding 65 off the edge of the iron or dampener.

The front faces of the irons a are provided with grooves i for receiving the edges of the articles to be ironed, and there are arranged for guiding the articles into and along the 70 grooves i projecting top and bottom strips $j j'$, attached to the frame of the ironer. The surface of one or more of the grooves i on the irons nearest the dampener is roughened in order to remove or turn over the rough or 75 fuzzy edges on the articles being ironed. k is the gas-supply tube, furnished with holes k' under each of the irons for heating the same. Any of the irons may be removed by lifting the pin b , which is seated in the top 80 and body of the frame and passes through the bearing l , integral with the iron a .

The dampener, Fig. 3, has the general shape of the irons a and is composed of the following parts: m is a spool, made of wood or 85 metal, turning on the spindle o and covered outwardly with felt, cloth, or similar material. This sits in the water, either wholly or partially filling the dampener c , which keeps the absorbent material always saturated with 90 water.

h'' shows the legs supporting the ironer.

Another method of mounting the irons and dampener is shown in Figs. 6 and 7. In this arrangement the dampener or irons instead of 95 swinging on a pivot move forward and backward in slots q , arranged in the uprights x , the dampener or irons being furnished with a projecting lip p'' , engaging with the guide q . The movement under pressure is controlled 100 by the weighted lever e , as in the other forms.

The operation of the machine is as follows: The dampener c is filled with water and the irons heated by the gas. Heat from the irons

is conducted to the edge projections j, j' and they become hot. When all parts of the machine have attained the proper temperature, the article is passed through over the dampener first and then over the heated grooves i of the irons and in contact with the heated projections j, j' . The dampener moistens the edge, the roughened grooves of the nearest irons smooth over and lay down any fuzzy edge on the article being ironed, and the other smooth grooves finish the operation of putting a finish on the edge of the article. The heated projections or guides j, j' finish off the upper and lower sides of the article adjacent to the edge. The dampener and irons being mounted pivotally and yieldingly on pivots b and being urged outwardly by the weighted levers e , the dampener and the heated grooves in the irons will always follow accurately and with the proper pressure the regular or irregular edge of the article being ironed.

To prevent the edges of the collars, &c., getting caught on the points of the guides j, j' , their edges p are rounded off, as shown in Fig. 5.

It is evident that instead of the weighted levers e a spring can be used, either in conjunction with the levers e or applied directly to the pivotally-mounted dampener and irons.

Having thus fully described and illustrated my invention, what I claim is—

1. In edge-ironing machines, the combination of a pivotally-swinging dampener, one or more pivotally-swinging irons having an edge-ironing groove, and means for causing the dampener and iron to follow the edge of the article operated upon, substantially as set forth.

2. In edge-ironing machines, the combination of a dampener pivotally mounted, a grooved iron or irons similarly mounted, and weighted levers for controlling the movement and pressure of said dampener and irons, substantially as set forth.

3. In edge-ironing machines, the combination of a pivotally-mounted iron having an ironing-groove on its outer surface, a weighted lever resting by one arm against the opposite surface of said iron and a stop operating in conjunction with said lever-arm to limit the swing of the pivotally-mounted iron, substantially as set forth.

4. In edge-ironing machines, a pivotally-mounted dampener, one or more irons similarly mounted and having a roughened ironing-groove, in combination with one or more pivotally-mounted irons having a smooth ironing-groove, and means for controlling the pressure and motion of said dampener and irons, substantially as set forth.

5. In edge-ironing machines, the combination of a dampener swinging so as to follow the edge of the article being ironed, grooved irons similarly mounted, projecting guides adapted to iron the surfaces of the article adjacent to the edge and provided with means for preventing the article catching on the edges of the projecting guides, substantially as set forth.

6. In edge-ironing machines, the combination of a swinging dampener so mounted as to recede under pressure and follow the edge of the article being ironed, and guides for directing the course of the articles operated upon, substantially as described.

7. In edge-ironing machines, the combination of a dampener so mounted as to recede under pressure and follow the edge of the article being ironed, one or more irons similarly mounted, and guides for directing the course of the articles operated upon, substantially as described.

Signed at New York, in the county of New York and State of New York, this 27th day of November, 1899.

WILLIAM H. RICKEY.
